UNITED STATES PATENT OFFICE.

CASPAR KISTLER, OF STERLING, ILLINOIS.

STEM WINDING AND SETTING WATCH.

SPECIFICATION forming part of Letters Patent No. 392,580, dated November 6, 1888.

Application filed May 5, 1888. Serial No. 272,981. (No model.)

To all whom it may concern:

Be it known that I, CASPAR KISTLER, a citizen of the United States, residing at Sterling, in the county of Whiteside and State of Illinois, have invented certain new and useful Improvements in Pendant Setting and Winding Watches; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 My invention has reference to certain improvements in pendant winding and setting watches, and pertains more especially to mechanism for optionally communicating the motion from the winding-pinion to the winding mechanism and setting mechanism, respectively, and for disengaging the outer and intermediate winding mechanism from the works when such works are removed from the case, and therefore not controllable from the winding-stem.

20 In reference to the first part of my invention—that of alternately and optionally connecting the winding-stem to the winding mechanism and the setting mechanism—my invention relates to certain novel mechanism for placing and holding the usual oscillating yoke, which carries the intermediate winding-wheel and intermediate setting-wheel at its opposite extremities, in such position that said intermediate wheels may be optionally thrown in or out of engagement.

25 It is well known that the works of watches are sold and handled and regulated largely outside of and independent of any special case. When the yoke above referred to is controlled wholly from the winding-stem, such works are uncontrollable when removed from the case, and, the intermediate setting-wheel being normally in engagement with a pinion which receives rotation from the hand-wheels, the running of the works, when separate from the case, involves the movement also of the main winding-wheel and winding-pinion and the intermediate winding and setting wheels. This is more 30 mechanism than the mainspring is required to operate when the works are in the case, inasmuch as in the latter situation the winding-stem is utilized to hold the intermediate setting-wheel out of engagement with the hand-

wheels. Therefore it frequently results that when the works have been regulated independent of the case and are subsequently placed in the case the less work required of the main-spring in the latter situation results in the watch running at a greater velocity.

35 In the drawings, Figure 1 is a view of the frontside of the ordinary pillar-plate of a watch provided with my invention, a portion of the case and said plate next the winding-stem being cut away to more fully illustrate the position and operation of my devices. Fig. 2 is a view of the opposite side of said pillar-plate, showing the location of the bell-crank lever 8, one end of which is projected through the winding-pinion in position to be oscillated inward by end pressure from the winding-stem. Fig. 3 is a detail of the lever 8. Fig. 4 is a detail of the rim of the case, showing the location and mode of seating the forked oscillating lever 9, the fork of which bestrides the usual annular recess in the winding-stem. Fig. 5 is a detail of said lever 9. Fig. 6 is a detail of a section of the outer edge of the pillar-plate, showing the location therein of the spring-lever 10. Fig. 7 is a plan view showing (enlarged) the oscillating yoke and parts adjacent thereto.

40 When the works are in the case, the spring-lever 10 permits the curved spring 11 to rise to the upper smaller portion of the lug 12 on lever 8, in which condition said lug is withdrawn from contact with the adjacent end of the yoke 4, and the curved spring 13, inserted in said yoke near the intermediate winding-wheel, draws that end of the said yoke inward and disengages the intermediate setting-wheel; 45 but when the works are in the case the latter forces the outer end of the short lever 10 upward, and thereby forces the spring 11 down behind the larger portion of the lug 12, when the adjacent end of said yoke is thrown inward and the intermediate setting-wheel controlled from the winding-stem, as hereinafter stated.

50 1 is an ordinary watch-case.
2 is the pendant, in which is longitudinally loosely seated the winding-stem 3.

55 4 is the usual oscillating yoke, carrying at one end the usual intermediate winding-wheel, 6, and at the other end the intermediate setting-wheel, 7, and under said yoke is centrally pivoted the usual main winding-wheel, 25.

60 8 is a bell-crank lever suitably pivoted at

100

105

its angle to the pillar-plate 14 near the edge of the latter, and has one of its arms projected inward and furnished with a post or lug, 12, which latter is projected through said pillar-plate in position to be forced to or from the adjacent end of the yoke 4.

9 is a slightly-curved lever, (see Fig. 5,) which is centrally pivoted on the rear side of the front flange of the case center and near 10 the opening in said case, through which the winding-stem 3 is projected, and in such relation to the latter that the forked end 15 of lever 9 bestrides the stem fitting into the usual annular recess, 16, formed in said winding-stem. The movement in and out of the winding-stem 3 imparts oscillation to the lever 9 about in the plane of the rear side of the pillar-plate 14.

17, Fig. 4, is the pivotal seat of lever 9, and 20 is a screw set in the case 1 from the rear.

18, Fig. 4, is a short post formed on the rear side of the front flange of case 1 in such relation to the adjacent end of lever 9 as that said end of said lever in its oscillations passes over 25 post 18, and is held by the latter at the different ends of the arc of oscillation of said lever.

The lever 9 is reduced in thickness near the end adjacent to post 18, which permits said end to spring slightly in passing over post 18. 30 The outer side of the post 18 has a beveled formation, and the outer side of the adjacent end of lever 9 is also beveled, such beveled ends assisting, respectively, the adjacent end of said lever to rise over said post in each direction.

The purpose of the lever 9 and post 18 is to limit the inward and outward movement of the winding-stem 3 in changing the position of the latter from winding to setting, and vice 40 versa, and also to hold said stem at the limit of its in and out thrusts, and particularly to prevent said stem from working outward during the process of winding. The forked end of the lever 9 may also abut against the wall 45 of the case 1 in the outward throw of said forked end. The back of the cavity in the crown of the winding-stem abuts against the end of the pendant and also limits the inward thrust of said stem.

50 The bell-crank lever 8 is pivotally seated against the side of the pillar-plate 14, and one of its arms, 19, is projected along the rear side of said plate to a point opposite to the central opening in the winding-pinion 20, and said 55 arm 19 is there bent at a substantially right angle outward and extended wholly through the winding-pinion 20 in position to be pushed inward by the inward thrust of the winding-stem 3. The other arm, 21, of lever 8 is projected inwardly from the pivotal seat of said lever, as aforesaid, along the rear side of plate 14, and there is there formed on the front face of said arm a lug, 12, which projects through said pillar-plate and lies against the outer 60 side of a lug, 22, formed on the adjacent end of said pillar-plate. The lug 12 is formed with an outward shoulder, 5, near its base, against

which shoulder the free end of the curved spring 11 rests when the winding-stem 3 is drawn outward, in which position the spring 7c 11 forces the lug or post 12 against the adjacent end of the yoke 4 and thrusts such end inward, carrying the intermediate setting-wheel into engagement with the pinion 23, adapted to engage the usual hand-wheel, the 75 latter not being shown.)

In the construction shown in Fig. 1 a pinion, 23, is used between the intermediate setting-wheel, 7, and the hand-wheel; but the intermediate setting-wheel, 7, can as readily be 80 adapted to engage directly with one of the hand-wheels, as is very frequently the case.

When the winding-stem 3 is pushed inward, its inner end presses against the outwardly-projecting end of arm 19 of lever 8, and by the 85 oscillation of lever 8 throws the opposite end of said lever outward, carrying the lug or post 12, and with it the spring 11, outward, so as to release the adjacent end of yoke 4 from outside pressure, in which condition the usual 90 spring, 13, acting on the opposite end of the yoke 4, draws said end inward and the intermediate winding-wheel into engagement with the winding-ratchet; but the spring 11, being stronger than spring 13, the spring 11, when 95 permitted to rest against its adjacent end of said yoke 4, will force such adjacent end inward notwithstanding the resistance of said spring 13 at the opposite end of said yoke.

A short post, 22, formed on the front side 100 of the pillar-plate near the free end of the spring 11 and on the inside of the latter, serves to limit the inner movement of said spring when the winding-stem is drawn out and said spring permitted to throw the intermediate 105 setting-wheel into operation. The post or stop 22 prevents the free end of spring 11 from pressing against lug 12 beyond a certain amount, and thereby prevents too great pressure of the intermediate setting-wheel upon the 110 pinion with which it engages.

The spring 11 is so formed and seated as that its free end if unresisted would rise on lug 12 above the shoulder 5 thereof and rest against the apex or smaller upper portion of said lug, 115 in which position the spring 13 at the opposite end of yoke 4 would draw its adjacent end of said yoke inward and disengage the intermediate setting-wheel. This is the condition when the works are separate from the case, 120 and therefore said works may be regulated independently of the case and disconnected from the yoke 4 and its adjacent mechanism, and in precisely the same situation and condition in which said works will be required to operate. 125 In order to control this upward tendency of the free end of the spring 11 when the works are in the case, and to compel said spring to remain in contact with the shoulder 5 of lug 12 on lever 8, I provide a radial lever, 10, pivoted centrally on the front side of the pillar-plate 14, with its inner end resting upon the upper side of the free end of spring 11 and its outer end in position to be engaged and forced 130

upward by the adjacent flange of the case 1 when the works are placed in the case. The upper forcing of the outer end of lever 10 of course forces the inner end of said lever downward and presses and holds the free end of spring 11 down behind and in contact with the shoulder 5 on lug 12, and junction being now formed with the winding-stem, the intermediate setting-wheel can be disengaged through the medium of said stem; but when the works are removed from the case or before they are placed therein the inner end of lever 10 is free to rise with the upward pressure of spring 11, and thereby permit the latter, as aforesaid, to rise to the smaller portion of lug 12 and permit the disengagement of said intermediate setting-wheel by the inward draw of the spring 13.

As the residue of the watch not specially described herein consists of the usual and well-known parts, I do not deem it necessary to show or describe the latter.

When my invention is used on hunting-case watches, the inner end of stem 3 is projected through the usual case-spring, and the inner shoulder on said stem actuates said spring.

What I claim as my invention, and desire to secure by Letters Patent of the United States, is—

30 1. The combination of the winding-stem 3, provided with the annular recess 16, the forked lever 9, adapted to bestride the stem and fit into the said recess, the lever 8, provided with lug 12, and the yoke 4, substantially as shown, and for the purpose described.

2. The combination of the winding-stem 3, seated loosely in pendant 2 and provided with annular recess 16, forked lever 9, adapted to bestride the stem and fit into the said recess, 40 pin 18, lever 8, provided with lug 12, spring 11, and yoke 4, substantially as shown, and for the purpose described.

3. In combination with the usual oscillating yoke, 4, provided at one end with the intermediate winding-wheel and at the other end with the intermediate setting-wheel, the lever 8, suitably pivoted and provided at one of its ends with the lug 12, adapted to engage intermittently one end of yoke 4, and further 50 provided with arm 19, projected outwardly in position to be engaged by the inward thrust of the winding-stem 3, springs 11 and 13, and winding-stem 3, seated loosely in pendant 2 of a watch, substantially as shown, and for the purpose described.

4. The combination of the winding stem 3, provided with the annular recess 16 and seated loosely in the pendant 2 of case 1, the lever 9, centrally pivoted in case 1 and provided with the forked end 15, adapted to bestride the stem and fit into the recess 16 and post 18, set in case 1, and adapted to stop lever 9 at each end of its arc of oscillation, whereby the inward and outward thrust of stem 3 is limited and said stem held, substantially as shown, and for the purpose described.

5. The combination of the case 1, winding-stem 3, loosely seated in the pendant 2 thereof, yoke 4, and lever 8, provided with arms 19 and 21, and pivotally seated in case 1, and having its arm 19 bent outward in position to be engaged by the inward thrust of stem 3, and having arm 21, provided with lug 12, adapted to intermittently engage and release 75 the yoke 4, substantially as shown, and for the purpose described.

6. The combination of case 1, the pillar-plate 14, pendant 2, winding-stem 3, loosely seated therein, oscillating yoke 4, centrally 80 pivoted to said pillar-plate, bell-crank lever 8, having one of its ends adapted to be thrust inward by the winding stem 3, and its other arm provided with lug 12 to intermittently engage the adjacent end of yoke 4, and springs 11 85 and 13, spring 11 being stronger than spring 13, whereby when the winding-stem 3 is pushed inward the lug 12 relieves the adjacent end of yoke 4 of the pressure of spring 11 and permits spring 13 to draw the adjacent 90 end of yoke 4 inward and engage the winding mechanism, and when the winding-stem is drawn outward the lug 12 is permitted to be crowded against the adjacent end of yoke 4 by spring 11, and the adjacent end of yoke 4 95 thrown inward and into engagement with the intermediate setting-wheel, substantially as shown, and for the purpose described.

7. The combination of the pillar-plate 14, the stop-post 22, seated on said plate, and spring 11, substantially as shown, and for the purpose described.

8. The combination of the yoke 4, pillar-plate 14, lever 8, pivotally seated thereon, lug 12, formed on said lever and provided with 105 shoulder 5, spring 11, adapted to press against the outside of lug 12 and to rise when uninfluenced to the upper portion of lug 12, and radial lever 10, centrally pivoted to said pillar-plate, and adapted when the works are 110 removed from the case, to permit the spring 11 to rise to the smaller portion of the lug 12 and allow the spring 13 to disengage the intermediate setting-wheel, and when said works are in position in the case to force the free 115 end of spring 11 down against the shoulder 5 of lug 12 in position for compelling the engagement of the intermediate setting-wheel, substantially as shown, and for the purpose described.

9. The combination of the case 1, pendant 2, winding-stem 3, seated therein and provided with the annular recess 16, the lever 9, provided with forked end 15, adapted to engage said recess, post 18, adapted to stop lever 9 at 125 each limit of its oscillation, lever 8, provided with lug 12, and yoke 4, substantially as shown, and for the purpose described.

In testimony whereof I affix my signature in presence of two witnesses.

CASPAR KISTLER.
